(57) CLAIM

The ornamental design for a combined pool cleaner and attachment, as shown.

DESCRIPTION

FIG. 1 is a top and right side perspective view of a combined pool cleaner and attachment showing our new design;
 FIG. 2 is a front side elevation thereof;
 FIG. 3 is a rear side elevation thereof;
 FIG. 4 is a left side elevation thereof, the right side elevation being a mirror image thereof;
 FIG. 5 is a top plan view; and,
 FIG. 6 is a bottom plan view.
